SPACE VEHICLE

Richard J. Brown, 1109 Edgewater Drive, Naperville, Ill.

Filed Dec. 4, 1961, Ser. No. 67,778

Term of patent 14 years

(Cl. D71—1)

Fig. 2.

Fig. 3.

Fig. 4.

Fig. 5.

Fig. 6.

Fig. 7.

FIG. 1 is a perspective view of a space vehicle, showing my new design with the wings thereof in an open position;

FIG. 2 is a side elevational view thereof with the wings folded;

FIG. 3 is a side elevational view of the space vehicle with the wings in an open position;

FIG. 4 is a front elevational view thereof with the wings closed;

FIG. 5 is a front elevational view of the space vehicle with the wings open;

FIG. 6 is a rear elevational view of the space vehicle with the wings closed;

FIG. 7 is a rear elevational view thereof with the wings open;

FIG. 8 is a plan view of the space vehicle with the wings open;

FIG. 9 is a plan view thereof with the wings closed; FIG. 10 is a bottom view of the space vehicle with the wings closed; and

FIG. 11 is a bottom view of the space vehicle with the wings open.

I claim:

The ornamental design for a space vehicle, as shown and described.
